(57) **CLAIM**

I claim the ornamental design for a combination waste collection and storage apparatus, as shown and described.

DESCRIPTION

FIG. 1 is a front left perspective view of a waste collection and storage apparatus;

FIG. 2 is a front right perspective view of the apparatus of FIG. 1;

FIG. 3 is a rear left perspective view of the apparatus of FIG. 1; and

FIG. 4 is a left side elevational view of the apparatus of FIG. 1;

FIG. 5 is a front elevational view of the apparatus of FIG. 1;

FIG. 6 is a right side elevational view of the apparatus of FIG. 1;

FIG. 7 is a rear elevational view of the apparatus of FIG. 1;

FIG. 8 is a top plan view of the apparatus of FIG. 1;

FIG. 9 is a bottom plan view of the apparatus of FIG. 1;

FIG. 10 is a front left perspective view of another embodiment of a waste collection and storage apparatus; and,

FIG. 11 is a front right perspective view of the apparatus of FIG. 10.

The broken lines show portions of the article which form no part of the claimed design.

1 Claim, 11 Drawing Sheets
